(57) **CLAIM**

I claim the ornamental design for a wrench, as shown and described.

DESCRIPTION

FIG. 1 is a perspective view of a wrench for a locknut of a given size.

FIG. 2 is a side view of the wrench of FIG. 1.

FIG. 3 is a front view of the wrench of FIG. 1.

FIG. 4 is a top view of the wrench of FIG. 1.

FIG. 5 is a bottom view of the wrench of FIG. 1.

FIG. 6 is a perspective view of the wrench of FIG. 1, illustrated with a locknut having a different number of tabs.

FIG. 7 is a side view of the wrench of FIG. 6.

FIG. 8 is a front view of the wrench of FIG. 6.

FIG. 9 is a top view of the wrench of FIG. 6.

FIG. 10 is a bottom view of the wrench of FIG. 6.

FIG. 11 is a perspective view of a wrench for a locknut of another size.

FIG. 12 is a side view of the wrench of FIG. 11.

FIG. 13 is a front view of the wrench of FIG. 11.

FIG. 14 is a top view of the wrench of FIG. 11.

FIG. 15 is a bottom view of the wrench of FIG. 11.

FIG. 16 is a perspective view of the wrench of FIG. 11, illustrated with a locknut having a different number of tabs.

FIG. 17 is a side view of the wrench of FIG. 16.

FIG. 18 is a front view of the wrench of FIG. 16.

FIG. 19 is a top view of the wrench of FIG. 16; and,

FIG. 20 is a bottom view of the wrench of FIG. 16.

(Continued)

Any portion of the wrench shown in broken lines is included for the purpose of illustrating environment and forms no part of the claimed design.
